(57) **CLAIM**

The ornamental design for a retractable interconnecting sports net apparatus, as shown and described.

DESCRIPTION

FIG. 1 is an upper perspective view of a first embodiment of a retractable interconnecting sports net apparatus showing my new design;

FIG. 2 is a top view thereof;

FIG. 3 is a front view thereof;

FIG. 4 is a bottom view thereof;

FIG. 5 is a rear view thereof;

FIG. 6 is a first side view thereof;

FIG. 7 is a second side view thereof, the second side view being opposite the first side view;

FIG. 8 is an upper perspective view of the first embodiment with four interconnected net segments;

FIG. 9 is an upper perspective view of a second embodiment of the retractable interconnecting sports net apparatus;

FIG. 10 is a top view thereof;

FIG. 11 is a front view thereof;

FIG. 12 is a bottom view thereof;

FIG. 13 is a rear view thereof;

FIG. 14 is a first side view thereof;

FIG. 15 is a second side view thereof, the second side view being opposite the first side view;

FIG. 16 is an upper perspective view of a third embodiment of the retractable interconnecting sports net apparatus;

FIG. 17 is a top view thereof;

FIG. 18 is a front view thereof;

FIG. 19 is a bottom view thereof;

FIG. 20 is a rear view thereof;

FIG. 21 is a first side view thereof; and,

FIG. 22 is a second side view thereof, the second side view being opposite the first side view.

The dash-dash broken lines in the drawings illustrate portions of the article that form no part of the claimed design.

(Continued)

The retractable interconnecting sports net apparatus is shown with symbolic break in its width. The appearance of any portion of the article between the break lines forms no part of the claimed design.
